Witnesses;

Chas. C. Whiteman

H. D. Penney

By his Att'y,

Inventor:
William H. Bassett.

W.M. 1.

F. W. Richards

UNITED STATES PATENT OFFICE.

WILLIAM H. BASSETT, OF EAST ORANGE, NEW JERSEY, ASSIGNOR TO POWERS ACCOUNTING MACHINE COMPANY, OF NEW YORK, N. Y., A CORPORATION OF DELAWARE.

STATISTICAL RECORD-CARD.

1,346,162.

Specification of Letters Patent. Patented July 13, 1920.

Application filed August 29, 1918. Serial No. 251,927.

To all whom it may concern:

Be it known that I, WILLIAM H. BASSETT, a citizen of the United States, residing in East Orange, in the county of Essex and 5 State of New Jersey, have invented certain new and useful Improvements in Statistical Record-Cards, of which the following is a specification.

This invention relates in general to statistical cards for use with accounting machines, and more especially to record cards to be perforated for use with accounting machines of the type known as the Powers accounting machines.

15 Among the main objects of the present invention it is aimed to provide a card by which the surface area of the card can be used to the best advantage with a minimum loss of paper.

20 In practice, for a given accounting machine, the cards must all be of a standard size. With certain records, it has been found that the columns of records required would only fill a part of the card. In other 25 words, a large part of the card would be wasted. To this end, the present invention aims to provide a card of standard size which may be used for a plurality of records and thus the portion otherwise wasted, effectively used.

With many accounting systems, using these accounting machines and cards, there are balancing records to be taken, as for instance, in ordinary bookkeeping, a debit 35 record to balance a credit record, inventories, a record of goods bought and sold, and in railroading, a list of outgoing and incoming trains, cars and the like. To this end, the present invention aims to provide a 40 card in which the two so-called balancing records may be recorded on the same card, the advantage of which is self-evident and need not be enlarged upon.

A special feature of the present invention 45 is the provision of a card for balancing records as aforesaid on which two records are to be made, a record on one portion of the card and a record on the other portion of the card, the record portions being inverted relative to one another that is, when 50 the card is set up for reading one record and that in the present instance the record on the left portion of the card, the other record will be inverted, and the corners of the re-

spective portions of the card so marked that 55 the cards may with facility be arranged in piles according to the class of records to be recorded, thus when debit and credit records are to be recorded, all of the cards may quickly be arranged so that only the debit 60 records may be recorded.

These and other features, capabilities and advantages of the invention will appear from the subjoined detail description of one specific embodiment thereof illustrated in 65 the single figure in the accompanying drawings.

The card C represents in the present instance a card of standard size for use with accounting machines of the type known as 70 the Powers accounting machines, and is divided generally into the two areas or record portions 15 and 16, the area 15 when turned for recording, appearing on the left half of the card, while the area 16 at such time appears inverted and on the right half of the card, this arrangement of course being inverted when the card is turned so that the area 16 is positioned for recording. The areas 15 and 16 are provided with a plural- 75 80 ity of columns of data 17 as is usual with such statistical cards, each column having one or more rows of indications or indicia to be perforated according to the data to be recorded.

85 Thus, referring to the drawing, the orders portion or end of the card, by way of example, would be perforated as shown, and the reading would be an order on the 2nd day of the 3rd month of 1914, at plant 5, 90 customer - symbol 210, customer - code 451, type 43, cylinder number 333213, the plant supposedly being one manufacturing cylinders. The insheet portion or end of the card is perforated and read to show the in- 95 sheet or balancing record.

In the present instance, the embodiment 100 illustrates a card used with a plant manufacturing cylinders which may be returned for repair, and thus the area 15 is marked "Orders" to indicate the original shipment of the cylinder, which is a debit against the customer, and the area 16 "Insheets" to indicate the return of the cylinder for repair which is a credit to the customer. To distinguish 105 the areas 15 and 16 and thus facilitate arranging the cards in piles according to the data to be recorded, the upper left hand

corner of the area 15 is cut at 18, while the corresponding corner of the area 16 is left square. This arrangement of marking the respective corners may of course be similarly extended to money debit and credit record cards and the like.

It is obvious that various changes and modifications may be made to the details of construction without departing from the general spirit of the invention.

I claim:

1. A card of the type adapted for controlling accounting machines, said card having a pair of record portions, each portion being inverted relative to the other portion.
2. A card of the type adapted for controlling accounting machines, said card having a pair of record portions, each portion being provided with indicia, the indicia of one portion being inverted relative to the other portion.
3. A card of the type adapted for controlling accounting machines, said card having a pair of record portions, each portion being provided with vertical series of indicia, the indicia of one portion being inverted relative to that of the other portion.
4. A card of the type adapted for controlling accounting machines, said card having a pair of record portions, each portion comprising parallel vertical columns provided with vertical series of indicia, the indicia of one record portion being inverted relative to the other record portion.
5. A card of the type adapted for controlling accounting machines, said card having a pair of record portions, each portion comprising parallel vertical columns provided with vertical series of indicia, the indicia of one record portion being inverted relative to the other record portion, one of said record portions relating to credits and the other to debits.
6. A card of the type adapted for controlling accounting machines, said card having a pair of record portions, each portion comprising parallel vertical columns provided with vertical series of indicia, the indicia of one record portion being inverted relative to the other record portion, the upper left hand corner of one of said portions being cut away to distinguish such portion from the other record portion.
7. A card of the type adapted for controlling accounting machines, said card having a pair of record portions, each portion comprising parallel vertical columns provided with vertical series of indicia, the indicia of the right hand portion being up-side-down, and inverted relative to the left

hand portion, the indicia of the right hand portion being right-side-up.

8. A card of the type adapted for controlling accounting machines, said card being provided with a pair of record portions, each portion comprising a space extending across the upper part thereof and adapted to receive written data, and vertical parallel columns beneath said space, each column being provided with heading indicia and one or more vertical series of numeral indicia beneath said heading indicia, the indicia of one record-portion being inverted relative to the portion of the other.

9. A card of the type adapted for controlling accounting machines, said card being provided with a pair of record portions, each portion comprising a space extending across the upper part thereof and adapted to receive written data, and vertical parallel columns beneath said space, each column being provided with heading indicia and one or more vertical series of numeral indicia beneath said heading indicia, the indicia of one record-portion being inverted relative to the portion of the other, the indicia of one portion relating to credits and the other relating to debits.

10. A card of the type adapted for controlling accounting machines, said card being provided with a pair of record portions, each portion comprising a space extending across the upper part thereof and adapted to receive written data, and vertical parallel columns beneath said space, each column being provided with heading indicia and one or more vertical series of numeral indicia beneath said heading indicia, the indicia of one record-portion being inverted relative to the portion of the other, the indicia of the left hand record portion being right-side-up.

11. A card of the type adapted for controlling accounting machines, said card being provided with a pair of record portions, each portion comprising a space extending across the upper part thereof and adapted to receive written data, and vertical parallel columns beneath said space, each column being provided with heading indicia and one or more vertical series of numeral indicia beneath said heading indicia, the indicia of one record-portion being inverted relative to the portion of the other, the indicia of one portion relating to credits and the other relating to debits, the indicia of the left hand record portion being right-side-up.

WILLIAM H. BASSETT.
